UNITED STATES PATENT OFFICE.

JOSEPH A. FIRSCHING, OF UTICA, NEW YORK.

WINDING AND DYEING MACHINE AND METHOD OF WINDING AND DYEING YARN, THREAD, AND THE LIKE.

1,339,184.

Specification of Letters Patent.

Patented May 4, 1920.

Application filed March 5, 1919. Serial No. 280,722.

To all whom it may concern:

Be it known that I, JOSEPH A. FIRSCHING, a citizen of the United States of America, and resident of Utica, in the county of Oneida, in the State of New York, have invented new and useful Improvements in Winding and Dyeing Machines and Methods of Winding and Dyeing Yarn, Thread, and the like, of which the following, taken 10 in connection with the accompanying drawings, is a full, clear, and exact description.

This invention relates to certain improvements in winding and dyeing machines and method of winding and dyeing yarn, thread 15 and the like and pertains particularly to the intermittent dyeing of lengths of yarn uniformly as to the application of the dye, as to the extent of the dyed lengths and as to the spaced distance of said dyed lengths.

20 It is customary for the manufacturer of knit fabrics to rewind yarn as it comes from the manufacturer of yarns on to tapered or conical bobbins and as the winding is effected by tension applied through the rotary bobbin, the speed at which the yarn passes any predetermined point varies continually during each cycle of operation in accordance with the varying circumference of the bobbin. Therefore the intermittent 25 application of dye to the traveling yarn effected by moving the yarn at regular predetermined intervals into contact with a saturated wick in the manner described in Ainsworth Patent #1,274,972 produces an 30 irregular and non-uniform result, the spaced distance between the dyed lengths and the extent of the dyed lengths varying in accordance with the varying speed of the traveling yarn.

35 Further, the movement of the yarn across a stationary wick tends to dye one side of the yarn only and soon wears out the contacting portion of the wick.

An object of this invention is to produce 40 a method and a machine by which the dye will be applied to the yarn in uniform lengths, uniformly spaced by wiping contact of the yarn with a dye carrying element.

Further, as a distinct feature to so form 50 the dye carrying element and so move it relatively to the yarn as to roll the yarn while in contact with said element to uniformly apply dye to the entire circumference of the dyed lengths of the yarn. 55

Other objects and advantages relate to the details of construction and operation as will more fully appear from the following description contained in connection with the accompanying drawings in which— 60

Fig. 1 is an end elevation of a winding machine equipped with my invention.

Fig. 2 is a front elevation of a portion of the same machine.

Fig. 3 is a sectional view on line 3—3 Fig. 2.

Fig. 4 is a view partially in section on line 4—4 Fig. 2.

Fig. 5 is a section on line 5—5 Fig. 1.

Fig. 6 is a top plan of one end of the 70 tank shown in section in Fig. 5.

Fig. 7 is a section on line 7—7 Fig. 6.

Fig. 8 is a front elevation of a portion of the tank shown in Fig. 5.

Fig. 9 is a view partially in section of the 75 dye containing tank.

Fig. 10 is a section on line 10—10 Fig. 9.

The machine comprises a suitable framework —1— of the usual form and carrying the usual shafts for driving the different 80 parts of the machine. At each side of the frame there is provided an outwardly extending platform —2— serving as a support for a plurality of spools —3— of yarn, thread or the like in the form as it comes 85 from the manufacturer of yarns. The winding apparatus consists of spindles —3— mounted for rotation about vertical axes, each spindle adapted to carry a tapered or cone shape bobbin —4— upon 90 which the yarn is adapted to be wound preliminary to its use in the usual knitting machine. The yarn in its passage from spool —3— to bobbin —4— passes over a rest —5— projecting from and carried by 95 nut —6— threaded on to a vertically arranged screw threaded rod —7— carried by a cross bar —8— supported by a series

of vertical shafts —9— journaled in the framework and having their lower ends resting upon rollers —10— mounted upon the ends of levers —11— carried by rock 5 shafts —12— supported by the frame and extending from front to rear thereof.

In Fig. 2, I have illustrated but one of the shafts —9— and its operating mechanism whereas the present commercial machine utilizes three such shafts for supporting each bar —8—, but the construction of each shaft and the mechanism for elevating it is the same and will readily be understood from the disclosure of Fig. 2.

15 In the present commercial machine the shaft —12— is rocked or actuated by suitable mechanism driven from shaft —13— which shaft may in turn be driven from drive shaft —14— through the medium of 20 belt —15—.

The rocking movement given to shaft —12— will intermittently elevate shaft —9— and bar —8—, to thereby elevate rod —7—, nut —6— and rest —5— carried 25 thereby to properly move the yarn vertically of the cone shaped bobbin to cause the same to wind evenly and uniformly thereon. The mechanism so far described is old and well known. It will be understood that 30 the winding mechanism at one side of the machine is duplicated at the opposite side and the description of one of such mechanisms serves to describe both. At each side of the machine and carried by the frame 35 work thereof, is a tank —16— which may be formed to extend throughout the entire length of the machine and is provided with a dye applying element for each spindle —7—. This tank may be of any suitable form and 40 construction and as shown is formed of a metallic cylinder —17— having its ends closed by caps —18— which may be combined with nuts —19— and packing —20— to insure a liquid tight joint. The cylinder 45 —17— has arcuate portions of its wall removed preferably at spaced intervals conforming substantially to the spaced distance of spindles —7— said arcuate portions removed being equal in number to the 50 spindles upon that side of the machine. The openings thus formed are substantially closed by plates —21— having flanges —22— at the front and rear thereof for securing to the cylinder —17—, the surface 55 of the plates lying substantially in a chord of the circumference of the cylinder.

60 The plate —21— is provided with a groove —23— in its upper exposed face and this groove preferably as shown extends from one end along one edge of the plate for a short distance, then diagonally across the plate to a point spaced from the opposite end thereof and then along the opposite edge to said opposite end, for a purpose hereinafter described. The plate is pro-

vided with a central opening 28' leading from the interior of the cylinder —17— into said groove —23— and may have substantially circular pins —24— rising in the groove to guide the yarn through the diagonal portion of said groove.

70 For the purpose of applying dye to the traveling yarn a rotary dye applying element —25— is provided pivotally carried by a shaft having its ends mounted respectively in flanges —26— and —27— preferably integral with and extending downwardly from plate —21—. This element as shown is in the form of a circular wheel having its periphery projecting through the opening —28'— in plate —21—. As shown the element is built up from a pair of opposite metallic plates —28— confining between them an absorbent disk —29— of somewhat greater diameter than the plates. 80 The plates and disk are mounted upon a sleeve —30— in turn mounted upon shaft —31— having its end journaled in the flanges —26— and —27—. The yarn guided by the eye —32— and guide —33— passes 85 normally in contact with the periphery of the dye carrying applying element —25—.

The movement of the yarn across the element —25— diagonally of the plate —21— and at an angle other than a right angle 90 with the axis of said element will cause the dye applying element in its rotary movement to give to the yarn a rolling motion as it is wiped across the said element whereby the dye will be substantially uniformly applied to the entire circumference of the yarn.

95 The dye may be applied to element —25— in any suitable way and in the preferred manner illustrated is applied and the element rotated by a positively driven wheel —34— mounted upon a countershaft —35—, said wheel preferably embodying an absorbent or other disk —36— contacting with the disk —29— to frictionally drive the element —25—, as well as uniformly apply dye 100 thereto. The countershaft —35— may as shown be journaled in one end —18— of tank —16— and in bracket —37— carried by the cylinder —17—.

105 The method and apparatus for driving shaft —35— at a speed varying in accordance with the varying speed of the traveling yarn constitutes an important part of this invention and consists of a pulley —38—, belt driven from pulley —39— formed in 110 connection with and rotating with a cone shaped roller —40—, which cone shaped roller is adapted to be frictionally driven by a reversely arranged cone shaped roller —41— positively driven as from shaft 115 —14— by belt —42—.

120 The cone shaped roller —41— is mounted on shaft —42— having its opposite ends journaled in a substantially U-shaped casting —43— formed with a pair of legs —44— 130

adapted to rest upon bracket —45— carried by frame —1—, said casting secured to said bracket as by bolts —44— constituting a stationary mounting for said cone shaped roller. The oppositely disposed cone roller —40— is mounted upon a shaft —46— having its ends journaled in a U-shaped bar —47— pivotally carried by arms —48— projecting from casting —43—. The cone roller —40— is normally pressed toward the cone shaped roller —41— by springs —49— positioned between opposite ends of the bar —47— and the adjacent portions of casting —43— and the casting may 10 be provided with the seats —50— for receiving portions of the springs and bar —47— may be provided with an adjusting screw for properly tensioning the springs. These springs bear against the bar —47— below 15 the pivots —51— thereby tending to rock the bar about such pivots and hold the roller —40— in proper position.

For the purpose of effecting the variable drive required by this invention a loose belt 20 —52— extends between the rollers —40— and —41— and causes the one to frictionally drive the other at a speed dependent upon the position of the belt longitudinally of the rollers. As illustrative, if the belt 25 —52— lies between the rolls at a point where roller —40— is of largest diameter and roller —41— is of least diameter, roll —41— will drive roll —40— at a relatively slow speed, whereas, if the belt —52— lies 30 between the rollers at a point where the roll —41— is of largest diameter, such roll will drive roll —40— at a relatively high speed and as the relative proportions of the cone shaped rollers vary in a manner similar to 35 the variations in diameter of the cone shaped bobbin, the drive of roller —40— by roller —41— may be made to vary in accordance with the variation in speed of the traveling yarn as wound upon bobbins —4— if the 40 belt —52— can be made to vary its position between the cone rollers —40— and —41— in accordance with the movement of guide —5— controlling the vertical position of the traveling yarn relatively to the bobbin —4—.

This is accomplished by mounting belt —52— upon a roller —53— carried from a clip —54— slidably mounted upon bar —55—, which bar is carried by the upper 45 spaced ends of casting —43—. The clip —54— is connected by bar —56— with a rock arm —57— carried by the rock shaft —12—. By making the effective radius of rock arm —57— substantially the same as 50 the effective radius of lever —11— the movement of clip —54— along shaft —55— will conform with the movement of shaft —9— and guide —5— and the distance of movement will be the same so that the speed of

roller —40— will vary in accordance with 65 the speed of the traveling yarn.

The countershaft —35— and element 70 —25— will therefore, be driven at a speed varying in accordance with the speed of the yarn.

In order to effect intermittent dyeing of the yarn in the use of this machine it becomes necessary to move the yarn intermittently out of contact with the dye applying element and by utilizing countershaft —35— 75 as a driving agency for this purpose the lifting or elevating means will act upon the yarn at varying intervals dependent upon the speed of the traveling yarn to thereby effect dyeing in uniform lengths, uniformly 80 spaced. For this purpose a substantially U-shaped plate —58— is pivotally connected to flange —59— extending upwardly from plate —31— by bolt —60—, the arm —61— extending downwardly through 85 plate —21— and carrying a screw —62—, upon which the upper slotted end of pawl —63— is mounted. The pawl —63— is pivoted on bolt —64— carried by the arm —65— and the pawl has its end —66— 90 spring pressed into engagement with a corrugated wheel —67— mounted upon and rotating with shaft —35—. Rotation of corrugated wheel —67— moves pawl —63— about its pivot thereby rocking the plate —58— about bolt —60— and moving the finger —68— to elevate the yarn and move it from contact with the dye applying element —25—. The finger —68— may be formed of a single piece of wire return bent 95 to form a pair of hooks —69— adapted to be disposed upon opposite sides of wheel —25— and a raised connecting portion —70— lying above and extending across the periphery of said wheel. Normally the base 100 of the hooks lies sufficiently below the periphery of wheel —25— to permit the thread when tensioned to move across and in contact with the absorbent disk —29—.

In threading the yarn on the machine it 110 may be passed through eye —32— and permitted to lie in contact with post —24— without extending through the diagonal portion of the channel, but rather resting upon the concave portion of the upper surface of guide —33—. When the proper connection has been made the operator merely pushes the yarn or thread across the guide —33— until it passes down around the end of said guide and is drawn into the lateral concavity —70— properly positioning the yarn in the groove —23— for effecting dyeing operation.

Although dye may be supplied to the tank —16— in any suitable way, I have shown 115 a dye containing reservoir —71— suitably connected to pump —72— having its piston —73— driven by eccentric attachment to

pulley —38—. The pump is provided with an inlet pipe —74— and an outlet pipe —75—, the latter pipe communicating preferably with both tanks —16—. The pipes —74— and —75— adjacent the pump are provided with the usual opposed non-return valves —76— and —77—. By this means the liquid is continuously drawn from reservoir —71— and supplied to the tanks. Any surplus in the tank —16— is returned to the reservoir —71— through return pipe —78— which has a fitting —79— extending upwardly through the wall of tank —16— and opening at the top for telescopically receiving sleeve —80— having a stop shoulder —81—. The fitting —79— is provided with a slot —82— beginning at the internal surface of the lower wall of tank —16— and terminating some distance thereabove for registration with a smaller slot —83— formed in the sleeve —80—, the slot —83— determining the size and position of the discharge opening from tank —16—. Preferably sleeve —80— carries a screen —84— to retain any lint, etc., mixed with the dye. When the sleeve —80— is withdrawn from fitting —79— all of the dye will flow from tank —16— to receptacle —71—. An additional overflow pipe —85— is provided in communication with pipe —78— which prevents filling of tank —16— beyond a predetermined point even though the communication through fitting —79— and sleeve —80— becomes partially or wholly obstructed.

In the use of dye considerable evaporation takes place resulting in thickening of the dye and there has been no way of determining and indicating the amount of this evaporation. It has been impossible to accurately supply to the dye an additional quantity of the desired evaporable material and the full capacity of the dye has not been utilized. For this reason I provide reservoir —71— with a float —86— mounted upon a sleeve —87— vertically slideable on rod —88—. A clamp —89— is movably mounted upon sleeve —87— by means of a pair of spring pressed gripping levers —90— pivoted to the body of clamp —89—. A connecting rod —91— is pivotally mounted upon clamp —89— and has its opposite end pivotally secured to a pointer —92— in advance of the pivot —93— of said pointer. The pointer —92— is pivotally secured to the plate —94—, which plate in turn contains suitable indicia or a suitable scale of measure showing the amount of variation in the liquid contained in reservoir —71— as in pints, quarts or the like, or divisible parts thereof. By properly adjusting the clamp —89— as at night after the operation of the machine has ceased so that the pointer registers zero, the amount of the evaporation of the liquid dye in reservoir —71—

will be shown upon the dial —94—, by reason of the fact that the downward movement of sleeve —87— will cause a proportionate relative movement of pointer —92— so that the latter will indicate upon the dial the exact variation in the amount of liquid in reservoir —71—. Sufficient liquid as for instance, denatured alcohol may be added to reservoir —71— to bring the pointer back to zero thereby accounting for all evaporation and utilizing the entire capacity of the dye.

The operation of the machine will be readily understood from the above description, and although I have shown and described a specific construction of apparatus and parts thereof as illustrative of an embodiment of my invention, I do not desire to limit myself to the details of construction, form or operation of the apparatus or its parts as many changes and modifications in details and substitution of equivalents may be made without departing from the invention as set forth in the appended claims.

What I claim is:

1. The method of dyeing spaced lengths of yarn traveling at a varying speed comprising synchronizing the application of dye to the yarn with the varying speed of the traveling yarn.
2. The method of dyeing spaced lengths of yarn traveling at a varying speed comprising synchronizing the speed of the dye applying devices with the speed of the traveling yarn.
3. The method of dyeing spaced lengths of yarn traveling at a varying speed comprising varying the interval that the traveling yarn is in contact with the dye applying element in accordance with the speed of the yarn.
4. The method of dyeing spaced lengths of yarn traveling in a substantially predetermined cycle of speed variation comprising varying the spaced intervals that the traveling yarn is in contact with the dye applying element in accordance with the speed of the yarn.
5. The method of dyeing spaced lengths of yarn traveling at a varying speed comprising moving the yarn relatively to the dyeing element at intervals varying in direct relation with the speed of the traveling yarn.
6. The method of dyeing yarn and the like comprising causing the yarn to travel longitudinally at varying speed and moving the traveling yarn laterally into and out of contact with a dye applying element at intervals varying in direct relation to the varying speed of the yarn in its longitudinal travel.
7. The method of winding and intermittently dyeing yarn consisting in winding the yarn from a spool to a tapered bobbin so

that the yarn has a predetermined cycle of speed variation, and bringing the yarn into contact with the dye at intervals varied in direct relation with the variations in speed of the traveling yarn.

8. The method of winding and intermittently dyeing yarn consisting in causing the yarn to travel longitudinally at varying speed and applying dye to spaced lengths of the yarn at intervals varied in direct relation with the speed of the traveling yarn.

9. The method of dyeing spaced lengths of yarn traveling at a varying speed comprising synchronizing the speed of the dye applying devices with the speed of the traveling yarn, and rolling the yarn while in contact with the dye applying element.

10. The method of dyeing spaced lengths of yarn traveling at a varying speed comprising varying the interval that the traveling yarn is in contact with the dye applying element in accordance with the speed of the yarn, and rolling the yarn while in contact with the dye applying element.

11. The method of dyeing spaced lengths of yarn traveling in a substantially predetermined cycle of speed variation comprising varying the spaced intervals that the traveling yarn is in contact with the dye applying element in accordance with the speed of the yarn, and rolling the yarn while in contact with the dye applying element.

12. In a winding and dyeing apparatus, means for causing the yarn to travel longitudinally at a varying speed, and means for applying dye to the yarn at intervals varying in direct relation with the varying speed of the yarn.

13. In an apparatus for winding and dyeing yarn, means for causing the yarn to move longitudinally at varying speed, a dye applying device, and means for synchronizing the speed of the dye applying device with the speed of the traveling yarn.

14. In an apparatus for winding and dyeing yarn, means for causing the yarn to

move longitudinally at varying speed, a dye applying element, and means for moving the yarn relatively to the dye applying element at intervals varying in direct relation with the speed of the traveling yarn.

15. In a winding and dyeing machine, means for moving yarn longitudinally at varying speed, a dye applying element, and means for moving the yarn toward and from the dye applying element at alternate intervals varying in direct relation with the speed of the traveling yarn.

16. In an apparatus for winding and dyeing yarn, means for causing the yarn to move longitudinally at varying speed, a dye applying device, and means for synchronizing the speed of the dye applying device with the speed of the traveling yarn, and means for giving to the yarn a rolling movement while in contact with the dye applying element.

17. In an apparatus for winding and dyeing yarn, means for causing the yarn to move longitudinally at varying speed, a dye applying element, and means for moving the yarn relatively to the dye applying element at intervals varying in direct relation with the speed of the traveling yarn, and means for giving to the yarn a rolling movement while in contact with the dye applying element.

18. In a winding and dyeing machine, means for moving yarn longitudinally at varying speed, a dye applying element, and means for moving the yarn toward and from the dye applying element at alternate intervals varying in direct relation with the speed of the traveling yarn, and means for giving to the yarn a rolling movement while in contact with the dye applying element.

In witness whereof I have hereunto set my hand this 26th day of February, 1919.

JOSEPH A. FIRSCHING.

Witnesses:
